UNITED STATES PATENT OFFICE.

ROBERT ABBOTT, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

LAMP-RECEPTACLE.

1,101,376.

Specification of Letters Patent. Patented June 23, 1914.

Application filed November 13, 1912. Serial No. 731,169.

To all whom it may concern:

Be it known that I, ROBERT ABBOTT, a citizen of the United States of America, and residing at Bridgeport, in the county of 5 Fairfield and State of Connecticut, have invented a certain new and Improved Lamp-Receptacle, of which the following is a specification.

My invention relates to lamp receptacles 10 and particularly to the type commonly referred to as bull's eye or signal light receptacles which are primarily adapted to indicate the flow of current in the circuit in which the receptacle is installed, and the 15 object of my invention is to provide a compact and efficient device of this type in which the signal lamp may be readily installed.

In the accompanying drawings, Figure 1 20 is a plan, with face plate removed, of a combined switch, bull's eye and plug receptacle fitting in which my invention is embodied; Fig. 2 is a longitudinal section thereof on the line 2—2, Fig. 1; Figs. 3 and 25 4 are respectively plan and vertical section on the line 4—4, Fig. 3, of a simple bull's eye receptacle in which my invention is embodied.

The fitting shown in Figs. 1 and 2 comprises an insulating base 10 divided by partitions 11 and 12 into three chambers A, B 30 and C. In the first is arranged a switch mechanism 13, here shown of the single push button type; in the second, a single lamp 14; 35 in the third, terminals 15 for an attachment plug. The leading-in wires are secured to the binding screws 16—17 on the straps 18—19 which are integral with the switch terminals 20—21, while the switch terminals 40 22—23 are connected by conductor plates 24—25 with the lamp terminals 26—27 in chamber B, and the plug terminals 28—29 in chamber C, so that these appliances are placed in parallel with the switch circuit 45 when the switch is "on".

The lamp terminals in chamber B, with which my invention is principally concerned, are of such nature and so arranged that the lamp lies horizontally in the chamber and diagonally thereof, so that the porcelain base may be made of uniform depth 50 throughout its length and this depth is at the same time only that required for the standard types of switches and attachment 55 plug receptacles employed. The length of

the porcelain is likewise kept within the usual bounds of a three gang outlet box, so that a special outlet box to accommodate the fitting is not required.

The lamp receiving terminals comprise a 60 spring clip, the upstanding arms of which have bowed portions *x* and *y* to embrace the threaded shell 30 of the lamp base. In line with the axis of these bowed portions, the spring terminal 27 has a forward projection 65 *z* which, when the lamp is adjusted in position, is slightly pressed back by the center contact 31 of the lamp base and a good electrical connection established. The two terminals 26—27 are not only secured in position, but also brought into the switch circuit by securing screws 32 and 33 which connect them to the conductor plates 24—25 70 in the lower face of the base.

The fitting as a whole is adapted to be 75 mounted in an outlet box by means of the outwardly extending ears 34 into which the screws for the face plate 35, with bull's eye 36, are also threaded, in well known manner.

The embodiment of my invention shown in Figs. 3 and 4 is substantially the same as that shown in Figs. 1 and 2, except that here the switch and plug receptacle are 80 omitted and the wire terminals 37—38 are 85 formed on angled straps fitted in the opposite ends of the lamp receiving chamber and connected by conducting plates 39—40 to the lamp terminals. The latter are of the same character as in Figs. 1 and 2 and the 90 lamp lies as before diagonally of the chamber.

Obviously the particular structure shown and described is to be regarded as merely 95 illustrative of my invention.

I claim as my invention:—

1. A lamp receptacle of the character described, comprising an insulating base recessed to form a lamp receiving chamber, a face plate overlying said base and chamber, spring lamp terminals longitudinally spaced apart in said chamber and being shaped to receive and grip the usual screw plug base of an Edison type lamp and hold the lamp in said chamber with its axis in a plane substantially parallel to the plane of the face plate, as described.

2. A lamp receptacle of the character described, comprising an insulating base having a recess in its upper face of sufficient 110

- depth to accommodate a lamp placed on its side therein, a face plate overlying said base, and carrying a bull's eye above said chamber, in combination with spring lamp terminals 5 in said chamber, said terminals being shaped to receive and grip the usual screw plug base of an Edison type lamp and hold the lamp with its axis substantially parallel to the face plate.
10. 3. A lamp receptacle comprising a base, a face plate therefor, lamp receiving terminals insulated from each other and spaced longitudinally apart on said base and comprising a spring terminal open at its free end and having an upstanding bowed portion the axis of which is substantially parallel to the face plate to receive the shell contact of a lamp, and a second terminal having a portion in line with the axis of said bowed terminal to coöperate with the center contact of the lamp, substantially as described.
15. 4. A lamp receptacle comprising a base and lamp receiving contacts thereon insulated from each other and spaced longitudinally apart and comprising a clip with a pair of spring arms flared at their free ends and having oppositely faced bowed portions to receive a lamp shell contact and a second contact having a portion alined with the 20 bowed portion of the clip to coöperate with a lamp center contact, substantially as described.
25. 5. A lamp receptacle comprising a base, a clip mounted thereon and having a pair of upstanding substantially parallel spring arms with oppositely faced bowed portions forming a grip adapted to embrace a lamp shell contact, in combination with a second contact insulated and spaced from the clip 30 and having a portion alined with the axis of said bowed portion of the clip arms to coöperate with the center lamp contact.
35. 6. A lamp receptacle comprising a base, a clip mounted thereon and having a pair of upstanding substantially parallel spring arms with oppositely faced bowed portions forming a grip adapted to embrace a lamp shell contact, the free ends of said arms being outwardly flared to form a guide, in combination with a second contact insulated 40 and spaced from the clip and having a por-
- tion alined with the axis of said bowed portion of the clip arms to coöperate with the center lamp contact.
7. A lamp receptacle comprising a chamber, insulating body face plate therefor and lamp terminals insulated from each other and adapted to receive and hold a lamp within said chamber with its axis in a plane substantially parallel with said face plate, 55 said terminals comprising a pair of upstanding spring arms having oppositely faced bowed portions to receive the shell contact of the lamp and a spring terminal spaced therefrom and having a portion alined with said bowed terminal to coöperate with the center contact of the lamp.
8. A lamp receptacle comprising a chamber, insulating body face plate therefor and lamp terminals insulated from each other 60 and adapted to receive and hold a lamp within said chamber with its axis in a plane substantially parallel with said face plate, said terminals comprising a pair of upstanding spring arms having oppositely 65 faced bowed portions to receive the shell contact of the lamp and a spring terminal spaced therefrom and having a portion alined with said bowed terminal to coöperate with the center contact of the lamp, 70 the base of the chamber being recessed to accommodate the lamp bulb.
9. A lamp receptacle comprising a base, lamp receiving contacts thereon, conducting straps beneath the base and independently 75 connected to said lamp receiving contacts, said contacts being spaced longitudinally apart upon said base and comprising a pair of spring arms open at their free ends and having oppositely faced bowed portions to 80 receive the shell contact of a lamp and a second terminal having a portion alined with the axis of the bowed terminal to coöperate with the center contact of the lamp.
- In testimony whereof I have signed my 85 name to this specification, in the presence of two subscribing witnesses.

ROBERT ABBOTT.
